UNITED STATES PATENT OFFICE.

MARY JANIE LEACH, OF NORWICH, CONNECTICUT.

NEEDLE-HOLDER.

1,262,523.

Specification of Letters Patent. Patented Apr. 9, 1918.

Application filed February 24, 1917. Serial No. 150,680.

To all whom it may concern:

Be it known that I, MARY JANIE LEACH, a citizen of the United States, residing at Norwich, in the county of New London and State of Connecticut, have invented certain useful Improvements in Needle-Holders, of which the following is a specification, reference being had therein to the accompanying drawing.

10 The present invention has reference, generally to improvements in that class of inventions known as buckles, buttons and clasps and more particularly relates to a needle holder.

15 In making tatting and fastening it to a handkerchief, collar or other object, it is necessary to have an implement such as a crochet needle for punching through the cloth and also for drawing the thread 20 through the opening that has been punched. This implement ordinarily has to be dropped until it is needed again. Loss of time generally occurs in locating the needle, and inasmuch as it can not be punched in the 25 waist of the user, as a pin, it is necessary to provide means for holding it in a position in readiness for use when needed.

It is the principal aim and object of this invention therefore to provide an improved 30 pin adapted for removable engagement with the garment of the user for removably receiving the hooked end of a crochet needle for maintaining the needle when not in use, the pin being so positioned on the garment 35 that the needle may be readily removed therefrom when it is desired to use the same.

It is an additional object of this invention to provide improved attaching means for the tubular holding bar so as to prevent 40 the bar from moving while the hooked end of the needle is being inserted therein.

More particularly, the present invention embraces the provision of a crochet needle holder of such construction that it can be 45 used in the capacity of the usual bar pin when it is not desired to use the device when crocheting.

Among the other aims and objects of the present invention may be recited the provision 50 of a device of the character described with a view to compactness, and in which the number of parts are few, the construction simple, the cost of production low, and the efficiency high.

55 Other objects as well as the nature, characteristic features and scope of this inven-

tion will be more readily apparent from the following description taken in connection with the accompanying drawings and pointed out in the claim, forming a part of 60 this specification.

The preferred embodiment of the present invention is clearly illustrated in the accompanying drawings, in which:

Figure 1 is a perspective showing the invention applied to a portion of a garment such as a shirtwaist, the crochet needle being shown in position in the tubular holding bar. 65

Fig. 2 is an enlarged longitudinal section 70 of the device.

Fig. 3 is a transverse section taken on line 3—3 of Fig. 2.

Fig. 4 is a transverse section taken on line 4—4 of Fig. 2 in the direction in which the 75 arrow points.

Similar characters of reference are employed in all of the above described views, to indicate corresponding parts.

Referring now, more particularly, to the 80 accompanying drawings I provide a tubular bar 1 having one end closed and the opposite end open, the edges of the open end being beveled inwardly as indicated by the numeral 2 to facilitate the insertion of the 85 hooked end of a crochet needle 3 therein when it is not desired to use the needle.

With a view toward providing means for attaching the bar to an article of apparel such as a shirtwaist in a manner to prevent 90 undue movement of the tubular bar when in an attached position I have provided a main pin shank 4 the inner end of which terminates in an ear 5 which is pivotally mounted between the spaced ears 6 integral with 95 the outer surface of the bar adjacent the open end, by means of a pivot pin 7. The pointed end 8 of the pin shank is removably engageable with a hook 9 carried by the outer surface of the tubular bar 1 adjacent the closed end. An auxiliary pin shank has the inner end 10 formed integral with the main pin shank 4 adjacent the ear 6 100 and is offset as at 11 so as to arrange the pointed end 12 of the shank in spaced parallel relation with the shank 4 the pointed end 12 however terminating short of the pointed end 8 so as not to interfere with the engagement of the end 8 with the hook 9.

It will be noticed that when the parts are in 110 the position illustrated in Fig. 2 the longitudinal axes of the pin shanks are in the

same parallel plane which plane is also in spaced parallel relation with the longitudinal axis of the bar.

In applying the holder the pointed ends 5 and 12 of the pin shank should be inserted in the article 13 in the manner illustrated in Fig. 1, that is both of the pin shanks should be engaged in portions of the article and subsequent to the engagement of 10 the pin shanks with the article the pointed end 8 is engaged in the hook 9 so as to maintain the tubular bar 1 in a substantially rigid position and in spaced relation to the article and also in a vertical position so that 15 the hooked end of the needle 3 may be readily inserted in the bar 1. By the provision of the auxiliary pin shank it is readily apparent that the usual swinging movement which would be occasioned if 20 only one pin shank were employed, is obviated. If the owner of the pin is not crocheting the needle 3 of course may be removed and owing to the construction of the device it is likewise apparent that the same 25 may be used in the capacity of the usual bar pin for ornamental purposes.

It will be understood that the above description and accompanying drawings comprehend only the general and preferred embodiment of my invention and that various 30 minor changes in detail of construction, proportion and arrangement of the parts may be made within the scope of the ap-

pended claim and without sacrificing any of the advantages of my invention. 35

Having thus fully described my invention, what I claim as new and desire to secure by Letters-Patent, is:—

A needle holder comprising a tubular bar having one end closed and the other end open and adapted to receive the hooked end 40 of a crocheting needle, a hook integral with the outer surface of the bar and positioned transversely thereof adjacent the closed end, spaced ears formed integral with the 45 outer surface of the bar adjacent the open end and longitudinally of the bar and in alignment with the hook, a main pin shank, an ear formed on one end of the pin shank pivoted between the spaced ears on the bar, 50 the opposite end of the pin shank being pointed for removable engagement with the hook subsequent to being applied to an article of apparel, and an auxiliary pin shank having the inner end integral with the main 55 pin shank adjacent the ear and the outer end offset and pointed and arranged in spaced parallel relation with the main pin shank and in the same plane and adapted for engagement with the article of apparel 60 simultaneously with the engagement of the main pin shank therewith so as to coöperate with the main pin shank in maintaining the tubular bar in a substantially rigid position.

In testimony whereof I affix my signature. 65
